See & M. Caleb, Attns.

UNITED STATES PATENT OFFICE.

CHARLES HERMANOVICH, OF CHICAGO, ILLINOIS.

DESIGN FOR AN AUTOMOBILE-TRUCK BODY.

59,349.

Specification for Design.

Patented Oct. 11, 1921.

Application filed February 2, 1921. Serial No. 441,996. Term of patent 7 years.

To all whom it may concern:

Be it known that I, CHARLES HERMANOVICH, a citizen of the United States, residing at Chicago, in the county of Cook and State of Illinois, have invented a new, original, and ornamental Design for an Automobile-Truck Body, of which the following is a specification, reference being had to the accompanying drawing, forming part thereof.

The figure is a side elevational view of an automobile truck body, showing my new design.

I claim:

The ornamental design for an automobile truck body as shown.

In witness whereof, I hereunto subscribe my name this 31st day of January, 1921.

CHARLES HERMANOVICH.

Witnesses:

EDNA V. GUSTAFSON,
E. J. BOURGEOIS.
